UNITED STATES PATENT OFFICE.

JOSEPHINE F. BASCOM, OF HALIFAX, VERMONT, ADMINISTRATRIX OF GEO.
P. BASCOM, DECEASED.

PLOW.

SPECIFICATION forming part of Letters Patent No. 298,157, dated May 6, 1884.

Application filed January 23, 1882. (Model.)

To all whom it may concern:

Be it known that I, JOSEPHINE F. BASCOM, a citizen of the United States, residing at Halifax, in the county of Windham and State 5 of Vermont, administratrix of the estate of GEORGE P. BASCOM, late a citizen of Halifax, in the county of Windham and State of Vermont, deceased, (as by reference to the duly-certified copy of letters of administration 10 hereto annexed will more fully appear,) am the owner of a new and useful Improvement in Swivel-Plows, invented by the said GEORGE P. BASCOM in his lifetime, of which the following is a specification.

15 In the annexed drawings, Figure 1 is a side view of the device; Fig. 2, a rear view; Figs. 3 and 4 details.

This invention relates to the mold-board and attachments connected therewith; and the 20 object of this invention is to make a plow that will turn, like the ordinary swivel or side-hill plow, but which when turned and hooked into proper place will form a plow with a mold-board in shape like a stationary or landside 25 plow. To do this I make a plow with a stub of a mold-board, (marked A on the accompanying drawings,) on which sets a point, the same as in the old kind of plows, this being 30 formed by cutting what is the mold-board in the old style of plows off square across a few inches back of where the point sets on. From the stub mold-board thus formed a solid 35 iron arm, C, runs back, following the center line of the mold-board, and some four or five inches below where the center of the surface 40 of the mold-board would be. This arm is cast solid with the stub mold-board and turning part of the plow. On this arm, at about the middle of the mold-board, I set a rocker with a straight face; (marked D on drawings,) 45 this rocker being loose, so that it will rotate on the arm C.

Beyond the rocker D, and on the end of the arm C, is a casting, which is fastened solidly 50 to the arm C, and which holds the rocker D in place. This casting E has holes in each end, in which the plow is hooked.

Starting from the under side of the stub mold-board A, and extending down to the 55 arm C, is a flange, F, with a certain number

of holes in the upper edge immediately under the back edge of the stub mold-board A.

Starting from the holes in the flange F are an equal number of round or oval steel or iron rods, G G. These rods set into the holes in 55 the flange F, with a shoulder on the outside of the flange F of sufficient size to bring the surface of the rods even with face of the stub mold-board A; or the holes in flange F may be made of sufficient size to receive the rods 60 full size, bringing them at the starting-point from the stub mold-board the thickness of the casting below the surface of the stub mold-board; but whichever way this is done, the ends of the rods G G pass through the flange 65 F, and are fastened with a nut or pin, so that they cannot be drawn out, but not so tight but that they can turn or rotate each one independently of the others. These rods G G are perfectly straight, and run back far enough 70 to complete the length of the mold-board, passing over the face of the rocker marked D, and each rod is furnished with an offshoot or shoulder on both sides of the rocker D, and each rod is fastened to the rocker D by hav-

ing a bolt or pin pass through the shoulders on the rods, and through a corresponding hole in the rocker D, which holes in the rocker are made large enough so the bolt or pin can turn, as will be hereinafter explained. These rods, 75 instead of being fastened in the way above explained to the rocker D, may be fastened by a hook, latch, or any other contrivance that will hold the rods in place on the face of the rocker, and will yet allow them to rotate as 80 the rocker is turned into place. These rods G G being thus fastened in the stub mold-board A, which is stationary, and to the rocker D, which rotates upon the arm C, the rods G G, as the plow is swung into place on either side 85 of the beam, will twist into the form of a perfect mold-board, and when they are in this position the plow is fastened by a hook or latch (marked on drawings H) which passes through the casting E and outside of the rocker 90 D, and securely locks or fastens it in place. Upon the removal of the hook or latch the plow is not only at liberty to turn from side to side of the beam, but also the rocker D is free 95 to rotate upon the arm C, (and which the turn-

100

ing of the plow from side to side and the striking of the outside rod against the upright part of the plow will cause it to do,) thus twisting the mold-board upon either side into perfect 5 shape.

By the mechanism above described it will be seen that I make a plow which will turn as readily and is as easily operated as the ordinary swivel-plow, and which forms a perfect 10 mold-board upon each side from the bottom to the top, thereby admitting of the turning of a furrow from the shallowest possible depth to the deepest furrow that can be turned by a stationary or landside plow. 15 I am aware that reversible plows are old;

also, that such plows have been provided with rods extending back from the mold-board. In my device these rods extend back radially and their rear ends are free, thus allowing the furrow to be thrown off readily. 20

I do not claim this invention, broadly; but What I do claim is—

The combination of the mold-board A, flange F, rods G G, secured at one end to the flange F, and free at their other end, arm C, and 25 rocker D, as set forth.

JOSEPHINE F. BASCOM.
